ARM REST

Warren McArthur, Bantam, Conn., assignor, by
mesne assignments, to Reconstruction Finance
Corporation, New York, N. Y., a corporation of
the United States

Application November 19, 1943, Serial No. 510,883

3 Claims. (Cl. 155—198)

1

This invention relates to seats and particularly to those used in airplanes, railroad coaches and other vehicles of the type in which seats, usually two in number and independently adjustable, are arranged side by side.

An object of this invention is to provide an improved construction and arrangement of this type of seat, in which a removable arm rest is provided between the adjacent seats having an improved connecting means of such simplified construction as permits the ready assembly or disassembly of the arm rest as may be required.

This and other objects which will be apparent are accomplished by the invention hereinafter described and illustrated in the accompanying drawing in which,

Fig. 1 is a perspective view of a vehicle seat having a detachable center arm rest constructed in accordance with one embodiment of this invention, and

Fig. 2 is a side elevation, partly in section, of the center arm rest shown in Fig. 1.

As illustrated, the invention is shown in connection with a double passenger seat having two independently adjustable seat and back frames 5 and 6 mounted on a supporting frame 7 of tubular members including front and rear legs 8 and 9 and side arms 10 and 11 at each side of the frame.

Each seat and back frame is independently adjustable, each back being pivotally supported on a rear cross rod 12 while each seat is slidably supported on a front stretcher 13, a handle 14 being arranged on each seat to control a locking mechanism, not shown, for holding the seat in adjusted position.

In the present invention, a tubular center front leg 15 extends vertically upward to a point preferably somewhat below the top of the seat cushion, the upper end of the tubular leg being open. Similarly, a central, tubular, vertically extending rear leg 16 has an upper end projecting forwardly at an angle as best shown in Fig. 2, and terminating at a point between the back cushions. The open end of the rear leg is closed by a plug 17 secured in the leg by a screw 18 or other means and projecting outwardly beyond the end of the leg. A detent 19 having a spring pressed point 21 is secured in a radial bore in the plug 17.

A detachable arm rest 22 has a vertical front end 23 in which a plug 24 is slidably mounted, a radial pin 25 being secured in the plug and extending outwardly through a slot 26 in the wall of the arm 23. The opposite end 27 of the detachable arm rest is formed at the same angle as the

upper end of the rear leg 16, and can be telescoped over the rear leg plug 17 to abut the upper end of the leg 16, whereupon the spring detent 21 snaps into an opening 28 in the wall of the arm to hold the parts yieldingly together.

When assembling the detachable arm rest, the rear end is connected to the rear leg in the manner described, the plug 24 in the vertical front end first having been withdrawn into the arm by lifting the pin 25 to the top of the slot 26. When the arm is thus placed in position with the rear arm plug 17 telescoped within the open rear end of the arm, the front vertical end of the arm will abut and rest upon the open upper end of the front leg 15, whereupon, by releasing the pin 25 lowering the plug into the leg 15, the arm 22 will be detachably locked in place. For removal, it is only necessary to lift the front plug 24 to free the front end of the arm and permit the rear end to be drawn off the rear plug 17 against the tension of the detent 19.

The detachable arm is shown as having a cushion 31 and an ash receptacle 32.

It will be apparent that the invention can be variously modified and adapted within the scope of the appended claims.

What is claimed is:

1. An article of furniture comprising in combination, a supporting frame including front and rear legs formed by tubular members, a tubular arm rest, means removably connecting one end of the arm rest to one of the legs and comprising a plug slidably mounted in said one end of the arm rest and movable into telescoping engagement with said one of the legs, and means for preventing rotational movement of the plug with respect to the arm rest, and means connecting the other end of the arm rest to the other leg.

2. An article of furniture comprising in combination, a supporting frame including a front leg and a rear leg formed by tubular members, a tubular arm rest, means for removably mounting said arm rest on said legs, said means including an arm-engaging plug projecting outwardly from one of said legs and adapted to engage within one end of said arm rest, a connector plug slidably mounted in the other end of said arm rest and movable into telescoping engagement within the other of said legs, and a pin carried by said connector plug and extending through a slot in said arm for lifting said connector plug out of said other of said legs to disconnect said arm rest therefrom.

3. An article of furniture comprising in combination, a supporting frame including a front leg

formed by a tubular member extending substantially vertically upward and a rear leg formed by an upwardly extending tubular member having a forwardly extending end portion, a tubular arm rest, means for removably mounting said arm rest on said legs, said means including an arm-engaging plug projecting outwardly from the forwardly projecting end portion of said rear leg and adapted to engage within one end of said arm rest, a detent carried by said plug for engaging a recess in said arm, a connector plug slidably mounted in the other end of said arm rest and movable into telescoping engagement within the upper end of said front leg, and a pin carried by said connector plug and extending through a slot in said arm rest for lifting said connector plug out of said front leg to disconnect said arm rest therefrom.

WARREN McARTHUR.
